TYPEWRITING MACHINE

William F. Helmond, West Hartford, Conn., assignor to Underwood Elliott Fisher Company, New York, N. Y., a corporation of Delaware

Application January 15, 1936, Serial No. 59,168

29 Claims. (Cl. 197—183)

This invention relates to improvements in the stops or anvils for the type-bars of typewriting machines.

In typewriters of the Underwood class, a hard anvil or stop-ring is interposed in the path of the type-bar travel to the printing-point, the said anvil imparting a sharp rearward whip action and comparatively sharp forward recoil action to the type-bar, and thus insuring a clean type-impression.

To overcome the noise of impact on the unyielding stop-ring, and the accelerated deterioration to the type-bar structure resulting from these constantly repeated blows, resilient materials and structures have been substituted for the solid stop-ring. It has been found that such structures do not function satisfactorily because they do not arrest the type-bars at the proper point to produce the desired whip action, and throughout the full set of type-bars, the more frequently used characters wear the stop-ring unevenly, the irregularity of the type-impressions resulting therefrom detracting from the appearance of the work.

This invention discloses a stop-ring which, although resilient at the moment of impact of the type-bar, quickly assumes the characteristics of a uniform, solid abutment. It is a feature of the invention that the travel of each type-bar, regardless of its position in the type-bar assembly, is arrested at an exact point, and a uniform whip and recoil action is obtained. It is a second feature that the action is materially quieter, and less punishing to the type-bars. A third feature is that the wear on the stop-ring is not localized, and its component parts are inexpensive and easily replaceable.

My stop-ring is composed of a multiplicity of thin strips of substantially non-compressible, non-adhesive material, such as the resinoid "Phenolite", hard or vulcanized fiber, plated steel, or brass, placed one on another face to face to form a laminated structure. "Phenolite" is a trade-name for a material made from plastic phenol-condensate with which finely divided fibrous material has been intermixed to reduce brittleness. Such plastic-phenol-condensate product has been found particularly satisfactory, because it is non-resonant, and impervious to oil or moisture.

"Phenolite" or the like is commercially available in sheets of uniform thickness, and the stop-ring laminae made therefrom lie smoothly and flatly against each other. Another example of

plastic-phenol product is the well-known "Bakelite".

The laminae lie in normal contact with each other, and are non-compactly held in a vertical position against a smooth front surface of the type-bar segment by a thin, spring-mounted, steel facing-plate, which takes the punishment of the type-bars. An air film or space, estimated at .001 inch, separates the laminae by reason of the comparatively loose mounting. It will be understood that no effort is made to control the thickness of this air film, it being the natural result of the method of securing the laminae.

A dust-shield, mounted flush with the type-bar segment, and having an extended flange to cover the upper edges of the assembled stop-ring, is provided to prevent erasures or dust from working into the air spaces, which occurrence might impair the efficiency of the stop-ring.

To establish accurately the correct point at which the type-bar is arrested, the thickness of the compacted stop-ring may be held within close limits by the use of metal shims.

The type-bar strikes the steel facing-plate of the stop-ring, which retreats from the blow, and in so doing compacts the structure of the stop-ring by driving the air from between the laminae in the immediate area of the blow. The stop-ring thus becomes increasingly resistant to compression until at a definite point, controllable by the use of shims as previously mentioned, the stop-ring becomes a solidly compacted structure, arresting the further travel of the type-bar and inducing the desired whip action at the type-head.

Other features and advantages will hereinafter appear.

In the accompanying drawings,

Figure 1 is a perspective of the invention as applied to the type-bar segment of an Underwood typewriter, the stop-ring being partially in section to illustrate the laminated construction.

Figure 2 is a sectional elevation, substantially enlarged, of the construction of Figure 1, representing the condition of the stop-ring at the moment of contact of the type-bar.

Figure 3 is a view similar to Figure 2, illustrating the arrest of the type-bar by the compacted stop-ring, and diagrammatically illustrating the "whip" of the type-head to the platen.

Figure 4 is a magnified section of the stop-ring of Figure 3.

Figure 5 is a magnified sectional view of the stop-ring in repose.

Figure 6 is a perspective, disassembled view of the complete stop-ring.

Figure 7 is a section taken through 7—7 of Figure 1.

5 Figure 8 is a magnified view of a modified form of construction.

Figure 9 is a perspective and section of a lamina as employed in Figure 8.

A type-bar segment 15, having a smoothly machined front surface 16, is secured to a member 17 of a typewriting-machine frame. Slots 18, cut through a thickened lower portion 20 of the segment, accommodate type-bars 21, Figure 2, which are pivotally mounted on a fulcrum-wire 22, and arranged to be swung, in the usual manner, to cause type-heads 23 to come into printing-position against a platen 24. A type-guide 25, Figure 1, co-operates with the upper portion of the type-bars 21 to assure the correct printing-position. 10 Floating-frame guide rollers 26 are journaled in spring-brackets 27, said brackets being secured to the segment, as by screws 28, at each side of a stop-ring 30. The stop-ring 30 is wider than the usual solid abutment, and therefore the 15 brackets 27 are preferably inwardly offset, as shown in Figure 1, so that the rollers 26 may be in co-operative alignment with standard guide-slots provided in tongues (not shown) secured to the floating-frame of an Underwood machine, 20 all as described in my Patent No. 1,571,946, dated February 9, 1926.

The stop-ring 30 is composed of laminae 31, stamped out of thin sheets of Phenolite, fiber or metal. There are preferably at least four laminae, but, as shown in the drawings, a larger number may be used. The laminae are of uniform width, preferably $\frac{1}{8}$ ". They may be concentrically arcuate with the segment 15, and formed with their ends parallel to the upper edge of the said ring, as shown in Figure 6. It is important that each lamina be of uniform thickness throughout, but it is not essential that all of the laminae composing the stop-ring be of equal thickness, or of the same material. Phenolite, as it is readily obtainable in sheets 35 of closely uniform thickness, and as it does not crimp or develop a wavy surface during handling, has been found to be superior to other materials for the purpose.

50 A metal plate 32, Figures 1 and 6, preferably of thin spring-steel, concentric with the laminae, and of substantially equal width, is employed to take the punishment of the type-bars, and to hold the laminae 31 non-compactly in position against the front surface 16 of the segment 15. The plate 32 may be made in a single operation by a combination blanking, piercing or forming die. Flanges 33 disposed at the ends of the plate 32 and connected to the latter overlie the 55 upper surface of the segment 15, thus to prevent the lateral displacement of the laminae, and to protect the edges thereof against damage or the entry of dust. Mounting tongues 34, Figure 6, at the top and bottom edges of the plate 32, have inwardly offset portions 34^a and are punched or drilled with holes 35. As shown in Figure 7, the depth of the offset 34^a is less than the overall thickness of the assembled stop-ring, and the 60 said tongues are parallel to the surface of the facing-plate 32 and the face 16 of the segment. 65

Lugs 36, Figure 6, are also formed at the bottom edge of the plate 32, the said lugs being of greater length than the overall thickness of the stop-ring 30. Holes 37, Figure 1, are provided in 70 the segment 15 to receive the ends of the lugs 36.

An arcuate dust-shield 38, preferably of metal, is formed with a rear surface 40, to lie in close contact with the segment-surface 16 and with a forwardly-extending flange 41, to overlie the laminae 31 and a portion of the facing-plate 32 5 in spaced relationship therewith, as shown in Figures 4 and 5. The flange 41 is made wide enough to protect the relaxed stop-ring against the entry of dust and erasures, but not to extend beyond the forward edge of the facing-plate 10 when the stop-ring is fully compacted during operation.

The stop-ring is assembled, preparatory to mounting, by placing the laminae one on another, within the confines of the flanges 33, the 15 mounting tongue-offsets 34^a and the lugs 36 of the plate 32, these members forming a skeleton pocket in which the laminae are loosely held. The assembled stop-ring is held in position 20 against the segment-face 16 by screws 42, which have a shouldered portion 43 which slidably passes through the mounting holes 35. The facing-plate 32 yieldably confines the laminae by the action of spring-washers 44 interposed between the mounting tongues 34 and the heads 25 of the screws 42. The dust-shield 38 is securely held by the upper screws 42, which pass through holes 45 at the ends of the said shield, and confine the latter closely against the segment-surface 16 by the shoulders 43 of the screws. 30

The shouldered portions 43 act as a positive means of gaging the depth of insertion of the screws 42. As shown in Figure 7, the shoulders 43 of the lower screws are lengthened to compensate for the thickness of the dust-shield surface 40, and the facing-plate 32 thus confines the laminae 31 with equal tension. The spring-washers 44 are insufficient to hold the stop-ring structure in closely compacted form. The use of four mounting screws 42 and spring-washers 44 40 has been found sufficient to equalize the pressure exerted by the facing-plate 32 on the laminae 31. 45

To arrest the type-bars at the correct point, measured by the distance between the type-head 23 and the platen 24, at the point of arrest, and thus insure the proper whip action, the overall depth of the compacted stop-ring must be held within accurate limits. Because of the practical difficulty in obtaining Phenolite or other such synthetic material in extremely thin sheets, a 50 metal shim 46, preferably of brass, is inserted generally between the facing-plate 32 and the first lamina. Such shims are readily procurable in accurately gaged thicknesses, and it is thus practicable to maintain exact standards. 55

A cross-section of the assembled, relaxed, stop-ring, seen in magnified view in Figure 5, discloses that the laminae are separated by an air film 47. Experimental data and measurements indicate that the film between each lamina is approximately .001 inch in thickness, and is substantially uniform over the entire area of the stop-ring. 60

As the type-bar 23 strikes the facing-plate 32 during operation, the latter, being free to withdraw from the blow by the yieldable manner in which it is mounted, drives the laminae rearwardly, compacting them into a substantially solid structure as shown in magnified view in Figure 4, by forcing a large portion of the air out 70 from between the laminae. The cushioning effect of this air movement absorbs much of the impact of the type-bar and considerably lessens the noise of the contact. However, as each type-bar strikes the stop-ring with the same force, the 75

stop-ring is compacted in the same degree regardless of the position of the type-bar in the type-bar segment, and each type-head whips evenly to the platen. The whip action is diagrammatically shown in Figures 2 and 3, the latter showing the stop-ring compacted from the blow, and, in dotted lines, illustrating the extent of the whip.

Figures 8 and 9, in enlarged views, show a modified construction of the stop-ring 30, in which the laminae 31 are made up of thin iron or steel plates, on which a thin, even coating 48 of lead, cadmium or other metals is deposited, as by electro-plating. The preferred thickness 15 of the said coating is .005 inch. Lead is preferred, because it is itself non-resonant, and possesses excellent sound-deadening qualities when used with other metals.

As shown in Figure 8, the steel facing-plate 32 is employed to take the punishment of the type-bars, and the dust-shield 38 is also retained. It is an advantage of the modified form that the overall thickness of the laminae 31 may be closely gaged by suitable control of the 20 plating process, and it is generally unnecessary therefore to employ a shim to govern the total thickness of the assembled stop-ring. At each end of the shim 46, the flange or tab 33 may be formed at right angles thereto, to overlie the upper edge of the segment 15, as shown in Figure 1. The tabs 33 secure the shim 46 against any possibility of sliding laterally around the stop-ring when the machine is being handled during shipping, as the contact of one or the 25 other of said tabs with the segment prevents any appreciable movement of the shim in either direction. The tabs 33 also overlie the laminae 31, and therefore also prevent the latter from becoming detached, even though the machine be held upside down in the shipping case. It will be understood that the lamina immediately adjacent to the facing-plate 32 may be formed with flanges similar to 33, as shown on the shim 46, and for the same purpose.

Variations may be resorted to within the scope of the invention, and portions of the improvements may be used without others.

Having thus described my invention, I claim:

1. In a typewriting machine, the combination with type-bars and a segment or frame on which they are pivoted, of a stop-ring to arrest the travel of the said type-bars on their printing strokes, said stop-ring including a multiplicity of laminae, non-compactly held against the surface of the said segment by yieldable means.

2. In a typewriting machine, the combination with type-bars and a segment or frame on which they are pivoted, of a stop-ring to arrest the travel of the said type-bars on their printing 60 strokes, said stop-ring including a multiplicity of laminae, held against the surface of the said segment by means including a wear-resisting facing-plate to take the punishment of the type-bars, said plate having offset tongues, and means 65 co-operating with said tongues yieldably to hold said plate in contact with said laminae.

3. In a typewriting machine, the combination with type-bars and a segment or frame on which they are pivoted, of a sound-deadening stop-ring 70 to arrest the travel of the said type-bars on their printing strokes, said stop-ring including a multiplicity of non-resonant laminae, non-compactly held against the surface of said segment by a yieldably mounted wear-resisting facing-plate.

4. In a typewriting machine having a plurality

of type-bars pivotally mounted in a segment or frame, a stop-ring interposed in the path of said type-bars to arrest the travel thereof on the printing strokes, said stop-ring including a multiplicity of laminae, one of said laminae comprising a wear-resisting facing-plate, means for holding said laminae non-compactly against said segment, and means for preventing the entry of detritus between said laminae.

5. In a typewriting machine having a plurality 10 of type-bars pivotally mounted in a segment or frame, a stop-ring interposed in the path of said type-bars to arrest the travel thereof on the printing strokes, said stop-ring including a multiplicity of metallic laminae having a non-resonant coating, means for non-compactly holding 15 said laminae against the surface of said segment, and means protecting against the entry of detritus between said laminae.

6. In a typewriting machine having a plurality 20 of type-bars pivotally mounted in a segment or frame, a stop-ring interposed in the path of said type-bars to arrest the travel thereof on the printing strokes, said stop-ring including metallic laminae non-compactly held against the 25 surface of said segment, said laminae being electroplated, and means for protecting against the entry of detritus between said laminae.

7. In a typewriting machine, the combination with type-bars and a segment or frame on which they are pivoted, of a stop-ring to arrest the travel of the said type-bars on their printing 30 strokes, said stop-ring including a multiplicity of laminae, held against the surface of the said segment by means including a wear-resisting 35 facing-plate to take the punishment of the type-bars, said facing-plate loosely confining the said laminae against the segment by means including flanges disposed over the tops of said laminae and connected to said facing plate, inwardly 40 turned laminae-seating lugs on said plate, inwardly offset mounting tongues on said plate, headed screws passing through said tongues, in 45 slidable relationship therewith, into said segment, and spring-washers interposed between said tongues and the heads of said screws.

8. In a typewriting machine, the combination with type-bars and a segment or frame on which they are pivoted, of a stop-ring to arrest the travel of the said type-bars on their printing 50 strokes, said stop-ring including a multiplicity of laminae, held against the surface of the said segment by means including a wear-resisting facing-plate to take the punishment of the type-bars, said facing-plate loosely confining the said 55 laminae against the segment by means including flanges disposed over the tops of said laminae and connected to said facing-plate, inwardly turned laminae-seating lugs on said plate, inwardly offset mounting tongues on said plate, headed screws passing through said tongues, in 60 slidable relationship therewith, into said segment, spring-washers interposed between said tongues and the heads of said screws, and means 65 for gaging the depth of insertion of said screws into said segment.

9. In a typewriting machine, the combination with type-bars and a segment or frame on which they are pivoted, of a stop-ring to arrest the travel of the said type-bars on their printing 70 strokes, said stop-ring including a multiplicity of laminae, held against the surface of the said segment by means including a wear-resisting facing-plate to take the punishment of the type-bars, said facing-plate loosely confining the said 75

laminae against the segment by means including flanges disposed over the tops of said laminae and connected to said facing-plate, inwardly turned laminae-seating lugs on said plate having a length in excess of the thickness of the assembled stop-ring, said segment arranged to accommodate said excess length, inwardly offset mounting tongues on said plate, headed screws passing through said tongues, in slidable relationship therewith, into said segment, and spring-washers interposed between said tongues and the heads of said screws.

10. The combination with type-bars and a segment or frame in which they are pivotally mounted, said segment having a smoothly machined front surface, of a stop-ring including a wear-resisting plate, a multiplicity of flat-surfaced laminae interposed between said plate and said segment, and means yieldably holding said laminae therebetween, said laminae arranged to be compacted against said segment by the blow of the said type-bars.

11. In a typewriting machine, the combination with type-bars and a segment on which they are pivoted, of a sound-deadening stop-ring comprising a multiplicity of laminae, a metal facing-plate holding said laminae in such manner as to permit the free entry of a cushioning air-film therebetween, and means securing said plate to said segment to permit the rearward motion of said plate under the impact of the said type-bars and thus partially to expel the air from between the said laminae.

12. In a typewriting machine, the combination with type-bars having type-heads, and a segment or frame in which they are pivoted, of means to quietly arrest the travel of the type-bars at a definite point before printing, whereat the type-head, by accumulated momentum 40 springs to the platen to make the impression, said means comprising a stop-ring formed by a multiplicity of laminae individually loosely assembled on said segment or frame so as to initially yield one after the other under the impact 45 of the said type-bars and thereby finally compact into a non-yielding abutment.

13. In a typewriting machine, the combination with type-bars and a segment on which they are pivoted, of a sound-deadening stop-ring comprising a multiplicity of laminae, and a metal facing-plate holding said laminae in such manner as to permit cushioning air-film therebetween.

14. The combination with type-bars and a frame in which they are pivotally mounted, of a type-bar stop-ring including a multiplicity of laminae detachable from one another, and means mounting said laminae non-compactly face to face on said frame with the face of one lamina substantially against a surface of said frame, 60 said surface finally receiving the type-bar impact through said laminae as the latter become compacted under said impact.

15. In a typewriting machine, the combination with type-bars and a segment or frame on which they are pivoted, of a laminated stop-ring to arrest the travel of the said type-bars on their printing strokes, said stop-ring being arranged and mounted so that its laminae are normally loose and non-compacted but become compacted 70 facewise toward one another and against the surface of the said segment when arresting the type-bar strokes.

16. The combination with type-bars and a segment or frame in which they are pivotally mounted, of a stop-ring including a multiplicity of

laminae detachable from one another, said segment having a stop-ring-supporting surface, and means loosely mounting said laminae face to face and against said surface.

17. In a typewriting machine, the combination with type-bars and a segment or frame on which they are pivoted, of a loosely integrated non-resonant stop-ring formed by a multiplicity of laminae individually loosely assembled on said segment or frame so as to be pressed serially by the blow of the said type-bars and compacted into a non-yielding abutment of definite thickness.

18. In a typewriting machine, the combination with type-bars having a segmental mounting, of a set of buffer-plates superposed in substantially loose face to face assembly to constitute a slightly yieldable non-resonant stop for arresting the type-bars at the printing operation, said assembly being substantially loosely maintained against a surface of said mounting, said surface finally receiving the type-bar impact.

19. In a typewriting machine, the combination with type-bars having a segmental mounting, of a multiplicity of buffer-plates loosely superposed face to face in non-compacted assembly to constitute a slightly compactable and therefore slightly yieldable stop assembly for arresting the type-bars at the printing operation, said plates being made of non-resonant hard fibrous material, said assembly being loosely maintained against a surface of said mounting, said surface finally receiving the type-bar impact.

20. In a typewriting machine, the combination with type-bars having a segmental mounting, of a multiplicity of buffer-plates loosely superposed face to face in non-compacted assembly to constitute a slightly compactable and therefore slightly yieldable stop for arresting the type-bars at the printing operation, said plates being made, for durability and non-resonance, of hard sheet-metal thinly coated with a softer metal, said assembly being loosely maintained against a surface of said mounting, said surface finally receiving the type-bar impact.

21. In a typewriting machine, the combination with type-bars and a segment on which they are pivoted, of a sound-deadening stop-ring for accurately intercepting the type-bars just before printing, including a multiplicity of laminae, and means loosely mounting said laminae face to face on said segment in such manner as to permit cushioning air-film therebetween.

22. In a typewriting machine, the combination with type-bars and a segment on which they are pivoted, of a sound-deadening stop-ring for accurately intercepting the type-bars just before printing, including a multiplicity of laminae, and means loosely mounting said laminae face to face on said segment in such manner as to permit cushioning air-film there-between, said laminae including an outer wear-resisting face-plate of metal and a multiplicity of inner laminae, interposed between said face-plate and segment and made of non-metallic material that is substantially incompressible under the type-bar blows.

23. In a typewriting machine, the combination with type-bars and a segment on which they are pivoted, of a sound-deadening stop-ring for accurately intercepting the type-bars just before printing, including a multiplicity of laminae, and means loosely mounting said laminae face to face on said segment in such manner as to permit cushioning air-film there-between, said laminae including an outer wear-resisting face-plate of

- metal and a multiplicity of inner laminae, interposed between said face-plate and segment, and made of resinoid material that is substantially incompressible under the type-bar blows.
5. 24. A type bar abutment comprising a cage including a front striker plate, one or more noise-reducing filler plates mounted in said cage, and stops mounted on the ends of the cage for retaining the filler plate or plates against endwise displacement.
10. 25. A type bar abutment comprising a cage including a front striker plate, one or more noise-reducing filler plates mounted in said cage, and stops mounted on the cage for co-operation with the filler plate or plates to retain the latter against endwise displacement.
15. 26. In a key-operated machine, the combination with a fixed stop and a striking member, of a multiplicity of thin flexible laminations forming a pack which is backed against said stop and is provided with a cap struck by said member, said pack being caused by the impact of said member to pack more closely against said fixed stop, to form therewith a solid and accurate muting stop for said striking member.
20. 27. In a typewriting machine, the combination with type-bars and a segment or mount on which they are pivoted, of a stop-ring to arrest the travel of the said type-bars on their printing
25. strokes, said stop-ring including a multiplicity of thin flexible laminae, held lightly together against the surface of the said segment by yieldable means.
28. In a typewriting machine, the combination with type-bars having type-heads, and a fixed segment or mount in which they are pivoted, of means to quietly arrest the type-bars at a definite point before printing, whereat the type-head by momentum springs to the platen to make the impression, said means comprising a stop-ring formed by a multiplicity of thin flexible laminae lightly packed on said segment or mount so as to yield one after another under the impact of any of said type-bars and thereby finally compact 10 against said segment to form a non-yielding muting abutment.
29. In a typewriting machine, the combination with type-bars and a fixed segment or mount on which they are pivoted, of a laminated stop-ring 20 co-operating with said fixed segment to arrest said type-bars at their printing strokes, said laminae being thin and flexible but normally loose and non-compacted, and being compressible facewise against one another and against the 25 surface of said segment when arresting the type-bars, for muting the type-bar blows.

WILLIAM F. HELMOND.
